UNITED STATES PATENT OFFICE.

JOHN A. RATHBONE, OF DETROIT, MICHIGAN.

MOLDING MACHINE.

Application filed March 24, 1924. Serial No. 701,529.

The invention relates to molding machines of that type more particularly designed for use in forming multiple or stack molds. With such constructions the cope and drag patterns are opposed to each other, the former being carried by a movable ram and the latter being held stationary on the frame. The flask with a superposed sand frame is placed on the ram so as to surround the cope pattern and is filled with loose sand. Thus in the upward stroke of the ram the sand is compressed in the flask between the two patterns, forming mold cavities at both top and bottom. The flask is then removed and stacked with other flasks forming a series of superposed mold cavities having sprue connections through which the molten metal may be introduced.

With machines of the type just described it is important to have a high speed of operation in order to increase the output, but it is equally important to preserve the formed molds from injury. Thus during the drawing of the pattern too great speed may result in breaking the mold surface and render the mold useless. To avoid such result it is necessary to retard the downward movement of the plunger, which has heretofore been accomplished by the use of a dash pot. The mold is drawn from the drag pattern with little difficulty, as said pattern is above, but the drawing of the cope pattern is a more delicate operation. This is accomplished by arresting movement of the flask during the continued descent of the ram and cope pattern, but, as just stated, the movement must be so retarded as to perform such operation without injury to the mold. This necessarily slows the operation of the machine and increases the length of time for each cycle.

It is the object of the present invention to increase the speed and output of the machine without any detrimental action and to this end the invention consists in the means employed for producing a variable speed, which is as high as possible during the greater part of the movement of the ram, but is retarded during the intervals in which the patterns are drawn. The invention further consists in various features of the construction as hereinafter set forth.

In the drawings:

Figure 1 is a sectional front elevation of the machine;

Figure 2 is an enlarged sectional view of a portion of Figure 1.

In general construction the molding machine to which my improvements are applied comprises a base A having rigid columns B and B' rising therefrom with a swinging head C pivotally mounted at the upper end of the column B and detachably locking with the column B'. D is a cylinder formed centrally of the base A. E is a piston engaging said cylinder and F the ramming head mounted on said piston. The head F is provided with a plurality of upwardly extending lugs F' for supporting an annular flask frame G, which in turn is adapted to receive and support the flask H. These parts are aligned by pins I projecting upward from the ramming head and engaging registering apertures in the frame and flask. Within the flask frame is arranged an annular vibrator frame J, which in turn carries the supporting plate for the cope pattern detachably secured thereto. Secured to the swinging head C is an upper ramming head K to which the drag pattern plate L is attached. This is so arranged as to register with the opening in the sand frame and flask and to enter the same during the upward movement of the ram.

Beneath the flask frame G and cut away to avoid the lugs F' on the lower ramming head F is a stool plate M. The function of this plate is to separate the flask frame from the pattern plate and this has heretofore been accomplished by engaging supporting lugs with the stool plate so as to completely arrest its movement. Such a construction will affect the drawing of the pattern from the mold, but, as has been stated, the movement of the ram must be sufficiently slow to avoid injury.

As specifically shown in the drawings, I substitute for the usual means of completely arresting the stool plate mechanism by which its movement is merely retarded so that the differential will draw the pattern from the mold. This mechanism comprises cams N pivotally mounted at opposite ends of the ram having outwardly extending actuating arms N' for engaging bearings O mounted on the columns or other stationary part. The cams N engage roller bearings P mounted in bifurcated outer extensions of the stool plate and the arrangement is such that when the arms N' contact with the bearings O, the cam will be rotated in contact with the rollers P and will gradually separate the pattern from the mold. It will be noted,

however, that the stool plate may continue to descend with the ram, but that it moves at a slower rate so as to produce the desired differential.

5 While I have described a specific means of producing the differential movement, it is obvious that other constructions may be devised for the same purpose. All that is required is that the velocity of movement separating the pattern from the mold is less than the normal velocity of the ram during its descending movement, so that a greater speed may be imparted to the ram without injury to the mold.

15 The operation will be understood from the above description, but in brief is as follows: The ram F is normally at the lower end of its movement and to engage the flask and sand frame therewith the cross head C
20 is first swung out to provide the necessary clearance. When these parts are in position, sand is filled in to the flask and frame and struck off level with the top of the frame. Movement is then imparted to the piston
25 E through suitable pneumatic connections (not described), which imparts a rapid upward movement to the flask. The velocity is such that the inertia of the sand when contacting with the drag pattern will cause it to fill all parts of the pattern and with the further compression of the ram produce the necessary density. The downward movement of the ram is controlled by suitable means such as the dash pot Q, but a much more
30 rapid movement is permitted than with the constructions heretofore used. Thus the inertia of the parts will retard the acceleration of the ram when separating the mold from the drag pattern on the upper ramming head, and furthermore this operation can be performed at greater speed than the separation of the cope pattern. Thus the ram will descend quite rapidly, but before it completes its movement the cam N and associated parts will operate to slowly separate the cope pattern from the mold a sufficient distance to break the contact, after which the further descent of all of the parts is at the speed of the ram.

50 What I claim as my invention is:

1. In a molding machine, the combination

with a reciprocatory ramming head, a mold flask and a cooperating pattern which is separated from the mold during movement of said head, and means for causing a differential movement of said flask and pattern

2. In a molding machine, the combination with a reciprocatory ramming head, a mold flask and a pattern, of means for drawing the pattern from the mold in said flask during the return movement of said reciprocatory ramming head, and means for differentially moving the flask for retarding the drawing movement relative to the normal velocity of return movement of said head. 60 65

3. In a molding machine, the combination with a reciprocatory ramming head, a mold flask, a pattern which is separated from the mold in said flask during the return movement of said head, means for controlling the velocity of return movement of said head, and cooperating means for controlling the relative velocity of mold and pattern during separation of the one from the other. 75

4. In a molding machine, the combination with a reciprocatory ramming head, a mold flask and a pattern both normally carried by said head, of means for drawing the pattern from the mold in said flask during the return movement of the head, and means for differentially moving said flask and head during said drawing movement.

5. In a molding machine, the combination with a reciprocatory ramming head, a mold flask and a pattern, both normally carried by said head, and means operating during the return movement of said head for moving said flask at a velocity less than the normal velocity of return movement of said head. 85 90

6. In a molding machine, the combination with a reciprocatory ramming head, a mold flask and a pattern normally carried by said head, of means operating during the return movement of said head for retarding movement of said flask relative to the velocity of movement of said head and pattern carried thereby to effect a relatively slower drawing of the pattern. 100

In testimony whereof I affix my signature

Whereof I am my signatur
JOHN A. RATHBONE.
